UNITED STATES PATENT OFFICE

2,486,979

FORM FOR CASTING FOUNDATION FLOORS

Arthur R. Raymond and Mae Jones Raymond,
West Englewood, N. J.

Application September 24, 1947, Serial No. 775,834

2 Claims. (Cl. 25—131.5)

1

This invention appertains to novel and useful improvements in building constructions.

An object of this invention is to more efficaciously, easily and conveniently pour a foundation for a house, store or other structure.

Another purpose of this invention is to provide extremely inexpensive forms to be used in conjunction with the pouring operations.

Another purpose of this invention to provide a structure of the character described which is readily adjustable to suit many conditions of operation and which is extremely economical to utilize.

Other objects and features of novelty, such as ease of fabrication, will become apparent to those skilled in the art, in following the description of the preferred form of the present invention, illustrated in the accompanying drawings, wherein:

Figure 1 is a plan view of the preferred form of the present invention;

Figure 2 is a side view of the invention shown in Figure 1;

Figure 3 is an end view of the invention shown in Figure 1;

Figure 4 is a sectional view taken on the line 4—4 of Figure 2;

Figure 5 is a perspective view of a selected element of the invention;

Figure 6 is a fragmentary perspective view of another element utilized in conjunction with the present invention;

Figure 7 is a longitudinal sectional view of the invention shown in Figure 1 and taken on the line 7—7 thereof and in the direction of the arrows;

Figure 8 is a perspective view of the arcuate segment forming an important part of the present invention;

Figure 9 is an enlarged detail view showing a method of connection utilized in conjunction with the present invention; and

Figure 10 is a pictorial end view of the invention.

Referring now in detail to the illustrated preferred embodiment of the present invention, like reference characters are used throughout to indicate similar parts thereof.

This invention has been conceived and developed to provide a device for more conveniently, economically and efficaciously preparing forms for use in conjunction with pouring the foundation and lower floor of building structures. Many adjustments may be made in the preferred form of the present invention, whereby many conditions of operation may be coped with with ease and facility.

2

Referring primarily to Figure 4, there is disclosed an arcuate section 10 having an offset portion 12 adjacent one end thereof. An identical arcuate section 14 having an identical offset portion 16 is provided in association with the first-mentioned arcuate section. These arcuate sections 10 and 14, respectively, are secured together at or adjacent the marginal edges thereof, opposite the said offset portions 12 and 16. An ordinary conventional bolt and nut construction generally indicated at 18 may be supplied for this connection. Of course, the ends of the arcuate sections may overlap as shown in Figure 4 and slots or apertures may be associated with the said bolt and nut construction for adjustment purposes.

Angle iron supports 20 are supplied on the arcuate sections for the purpose of receiving in seating relation supports 22 for retaining the arcuate sections in a predetermined, desired position.

The said offset portions 12 and 16 are utilized for the purpose of supplying a footing for the foundation to be poured in the forms to be described herein.

Side members 24 are secured to each arcuate section 10 and 14 and cooperate therewith for the purpose of receiving concrete therein. If desired, additional end plates 26 may be utilized in association with the side members 24 for additional support and for closing arch end openings when pouring concrete. Appropriately shaped openings 28 are formed in the end plates 26 to accommodate the ends of the supports 20.

Means for connecting the side members 24 to the said arcuate sections is provided. This means preferably consists of bolts 28 having conventional nuts thereon extending through suitable apertures, whereby adjustment may be effected between the side members 24 and arcuate sections 10. Of course, conventional pegs may be driven in the ground and support rods placed against the chucks 30 on the sides of the members 24 for support purposes.

Angle irons or other suitable equivalent stiffening members 32 may be utilized in conjunction with the side members 24 to provide the required rigidity in construction.

Means for connecting the side plates 24 is supplied. This means is preferably a plurality of tie rods 36 extending through suitable apertures in the said side plates and having conventional nut-threaded construction for securing purposes. This construction obviously permits of adjustment as desired.

The end plates 26 may be fixed at the terminal portions of the arcuate members or sections 10 and 14 and also at the terminal portions of the side plates 24. Suitable slots 38 may be supplied in the said end plates 26 for receiving the tabs 40 therein. These tabs are apertured for the purpose of receiving pegs therein which may be utilized for detachably connecting the forms together. Obviously, when the form is so constructed, concrete or the like may be poured therein and permitted to harden, thereby leaving an arched foundation which cannot be attacked by termites and which may easily receive radiant heat pipes therein. Also, the main portion of the foundation is spaced from the ground, thereby permitting more efficacious insurance against dampness and the like.

Going now to Figure 10, it will be noted that any number of sections may be joined to form varied size forms. All that is necessary is to obviate the use of end plates at the selected portions and substitute additional arcuate members along with the appurtenances contiguous thereto.

If so desired, a supporting construction generally indicated at 42 may be supplied in the archway beneath the said arcuate sections 10 and 14. This adjustable support apparatus is preferably composed of angle iron, or the like, extensibly adjustable members 44 and 46 having apertures 47 therein for accommodating the support rods 22. Internally threaded bosses 48 and 50, respectively, are secured to the said members 44 and 46 which are bolted together. Of course, a plurality of apertures may be supplied in conjunction with the bolted construction whereby efficacious lengthening may be effected. Received in the said bosses 48 and 50 are the terminal portions of the bolts 28, described above.

Due to the extreme simplicity achieved by this invention, a further description thereof is deemed unnecessary. However, variations may be made

herein without departing from the spirit of the invention. Accordingly, limitation is sought only in accordance with the scope of the following claims.

Having described the invention, what is claimed as new is:

1. A building mold comprising overlapping arcuate sections, means for connecting said sections at the overlapping portions thereof, and a support at the overlapping portions of said sections, side plates, means for adjustably connecting said side plates to each other including a tie rod having threaded securing means at the ends thereof, means for securing said side plates to said sections, offset portions in said sections and in said side plates for forming a footing, brackets secured to said arcuate sections for seating supports, end plates having apertures adjacent the edges thereof, tabs extending from said side plates and disposed in said apertures, and means in said tabs for retaining said end plates assembled with said side plates.

2. The combination of claim 1 and said end plates having openings therein accommodating the end portions of said brackets.

ARTHUR R. RAYMOND.
MAE JONES RAYMOND.
